MAGAZINE CATCH AND RELEASE.

1,138,378.

Specification of Letters Patent.

Patented May 4, 1915.

Application filed July 16, 1913. Serial No. 779,273.

To all whom it may concern:

Be it known that I, GRANT HAMMOND, a citizen of the United States, and a resident of Hartford, in the county of Hartford and 5 State of Connecticut, have invented a new and Improved Magazine Catch and Release, of which the following is a specification.

My invention relates to means for retaining and releasing the magazine of a firearm, 10 and an object of my invention, among others, is to provide a device of this class that shall be particularly efficient in its operation and one in which the presence or absence of a cartridge within the breech chamber may be readily ascertained.

One form of device embodying my invention and in the construction and use of which the objects herein set out, as well as others, may be attained, is illustrated in the 20 accompanying drawings, in which—

Figure 1 is a view in side elevation of a portion of a pistol embodying my invention, with parts broken away to show construction. Fig. 2 is a view in section through the handle on plane denoted by dotted line 2—2 of Fig. 1. Fig. 3 is a detail side view of a portion of a pistol embodying my invention with parts broken away to show construction, the opposite side of the pistol 25 from that shown in Fig. 1 being illustrated in this figure. Fig. 4 is a detail sectional view illustrating the mechanism, the plane of section being denoted by the dotted line 4—4 of Fig. 1. Fig. 5 is a detail view illustrating the means for manually releasing the magazine. Fig. 6 is a detail view illustrating the means for releasing the breech-bolt.

In the accompanying drawings the numeral 10 indicates the handle of a pistol embodying my improvement, this handle having a trigger guard 11 within which a trigger 12 is located. A receiver 13 is removably attached to the handle and a barrel 15 is secured to the receiver. Firing mechanism of any approved construction may be employed including a hammer 16, a sear 17, and other parts all of which will be readily understood by those skilled in the 45 art and for which reason further description is omitted herein, and specific illustration of the construction of the breech-bolt and its operating mechanism is not shown.

A magazine 18 is removably located within the handle, this magazine having the usual 55 feeding spring 19 acting against a follower 20 upon which the cartridges 21 rest. A retaining notch 22 is formed in one side of the magazine 18 within which the retaining lug 23 of a magazine retainer or holder 24 is 60 located. This retainer in the construction herein shown, is in the form of a catch of rectangular shape in cross section at one end, having an opening 25 within which a plunger 26 is located, the plunger having a 65 head 27 against which a spring 28 thrusts, this spring projecting within a recess in a button 29 forming a part of the retainer. This button 29 extends through the side of the handle to the outer surface thereof 70 where it is accessible for manual operation. The head 27 rests against the surface of a wall of a recess in the back part of the handle as clearly shown in Fig. 4 of the drawings. An actuating bolt 30 is mounted in a recess in the side part of the handle, as clearly shown in Fig. 4 of the drawings, this bolt extending through the opening 25 in the retainer 24 and having a cam surface 31 to act upon the retainer, the bolt 75 being seated upon a spring 32 tending to force the bolt normally upward. A recess is formed in the side of the bolt for the reception of an actuating lever 33 and the upper end of the bolt engages with a breech-bolt holding pin 34, as shown herein, the end of the bolt being bent and engaging within a recess in the side of said pin. The pin 34 is located in an opening in the receiver and is moved by the actuating bolt into the path 80 of the breech-bolt 35 to hold it at the rearward limit of its play.

The actuating lever 33 is pivotally mounted upon a supporting plate 36 snugly fitting a recess 37 in the frame and held as by a pin 38. The end of the lever 33 engages a shoulder 40 on a spring detent 39 secured to the side of the magazine 18, the upper end of this detent resting against the cartridges or the follower 20 of the magazine, that, 95 when the last cartridge has been forced into the chamber in the breech, will rest against the under side of the breech-bolt 35, and retain the detent in engagement with the lever 33. This insures the retention of the 100 magazine within the handle until the last

cartridge has been fired so that it may be known that if the magazine is in place in the handle there are one or more cartridges ready to be fired. The bottom 41 of the 5 magazine is removably held in place as by means of a spring pressed pin 42 having a shoulder at one end against which the spring 43 presses. The opposite end of the spring presses against the inner surface of a flange 44 on the bottom. Each end of this holding pin is arranged to pass through openings in the flange 44 and in the wall of the magazine.

In the operation of the device, the trigger 15 being pulled and the cartridge exploded, the breech bolt 35 is forced backwardly operating the mechanism in a manner well known to devices of this class. As the breech-bolt is forced backward, its front end 20 passes behind the breech-bolt holding pin 34 but the holding lever 33 being held by the shoulder 40 this holding pin cannot move from its position. When the last cartridge, however, has been forced into its chamber in 25 the breech, the detent 39 will rest against the follower 20 at a point near the end of the detent. When the pistol is now fired as the breech-bolt travels backward, the follower 20 is released and moves upward permitting 30 the detent 39 to spring inward, releasing the lever 33, thus permitting the actuating bolt 30 to move upwardly under the influence of its spring 32. This action moves the breech-bolt holding pin 34 into the path of movement of the breech-bolt 35 retaining it at the backward limit of its play. This movement of the actuating bolt 30 causes the cam surface 31 to actuate the retainer 24, disengaging the lug 23 from the recess in the 35 magazine and permitting the latter to drop from its chamber either under the influence of gravity or a spring, if the latter shall be used. Upon inserting a loaded magazine, as the latter is moved upward the shoulder 40 40 engages the actuating lever 33 moving it to its normal position and resetting the parts by releasing the catch 23 to allow it to engage with the notch 22 and by disengaging the pin 34 from the breech-bolt. In case it 45 shall be desired to permit the breech-bolt to move forward when the magazine chamber is empty, a breech-bolt releasing lever 45 is pivotally mounted on the outer surface of the side part 46 of the frame, this lever having a lug 47 projecting through a slot 48 in said side part. This lug overlies a shoulder on the upper end of the actuating bolt 30, which at this time is at the upper limit 50 of its play, and by sliding the lever downward, the actuating bolt is moved downward carrying with it the breech-bolt holding pin 34 thus releasing the breech-bolt and allowing it to move forward.

While I have shown and described here- 55 in a preferred form of mechanism embody-

ing my invention, this construction may be departed from to a greater or lesser degree and yet be within the spirit and intent of the invention.

As a means for readily determining the 70 exact number of cartridges which the magazine may contain at any time, a series of holes 50 are formed in the side of the magazine, these holes being spaced a distance equal to that between the centers of the cartridges when located in place. 75

I claim:

1. A firearm including a frame containing a magazine chamber and supporting mechanism including a magazine located in 80 said chamber and having a movable follower, means for moving said follower, means for retaining the follower against movement after removal of the last cartridge from the magazine and for permitting movement of said follower after the last cartridge has been fired, and a magazine holder connected with said follower to be operated thereby in its final movement. 85

2. A firearm including a frame containing a magazine chamber and supporting mechanism including a magazine located in 90 said chamber and having a movable follower, means for moving said follower, a breech-bolt arranged to retain the follower 95 against movement after removal of the last cartridge from the magazine and to permit movement of the follower immediately after the firing of the last cartridge, a magazine holder, and an operative connection between 100 said holder and said follower to be operated by the latter in its final movement.

3. A firearm including a frame containing a magazine chamber, a breech bolt movably mounted therein, means for operating the 105 breech bolt, a magazine located in said chamber, a magazine holder, means for releasing said holder, a follower in the magazine movable into the path of the breech bolt and connected to operate the releasing means 110 when in said path, said follower being arranged to rest against the breech bolt in one position of said bolt, and means for moving the follower.

4. A firearm including a frame having a 115 chamber for a magazine, a magazine removably located in said chamber, a catch to retain the magazine in place, catch actuating means, a member borne by the magazine in engagement with a movable part thereof, 120 and connections between said member and catch actuating means to release the latter in the movement of said part.

5. A firearm including a frame having a 125 magazine chamber, a magazine located therein, a catch to retain the magazine in place, catch actuating means, a member borne by the magazine in the path of the movable follower thereof and arranged to be released in the upward movement of said fol- 130

- lower, and connections between said member and catch actuating means to release the latter.
6. A firearm including a frame having a magazine chamber, a magazine located in said chamber, a catch to retain the magazine in place, catch actuating means including a lever, and a detent movably mounted on the magazine and engaging said lever to retain it in place, said detent engaging the movable follower of the magazine and arranged to be released on the removal of the last cartridge from the magazine.
7. A firearm including a frame having a magazine chamber, a magazine located in said chamber, magazine releasing mechanism, a breech-bolt located in a breech-bolt chamber in the frame, a member connected with said releasing mechanism for operation to engage with said breech-bolt to hold it in its backward position, and means connected with said mechanism to actuate it, said means being operated by firing of the last cartridge formerly located in the magazine.
8. A firearm including a frame having a magazine chamber, a magazine located in said chamber, a breech-bolt to insert a cartridge from the magazine into the barrel, means for holding said bolt in its backward position, a magazine catch connected with said holding means to be automatically actuated thereby, and means connected with the magazine for releasing the breech-bolt holding means in the movement of the magazine to place it in its chamber.
9. A firearm including a frame having a chamber for a magazine, a magazine removably located in said chamber, a breech bolt to remove cartridges from said magazine, a member to hold the breech bolt against movement, means for holding the magazine in place, a lever operatively connected with a movable part of the magazine, and operative connections between said lever and the breech holding member, and between said lever and the magazine holding means.
10. A firearm including a frame having a chamber for a magazine, a magazine removably located in said chamber, means for holding the magazine in place, a breech bolt located in the frame, a member located to hold the breech bolt against movement, an operative connection between said member and the magazine holding means, and a lever
- connected with the breech bolt holding member and with a part in engagement with a movable part of the magazine.
11. A firearm including a frame having a chamber for a magazine, a magazine removably located in said chamber, means for holding the magazine in place, mechanism for releasing said holding means, said mechanism being connected for operation by a movable part of the magazine, and means for manually operating the magazine holding means independently of the operating mechanism therefor.
12. A firearm including a frame having a chamber for a magazine, a magazine removably located in said chamber, a holder to retain the magazine in place, a breech bolt movably mounted in said frame, a breech bolt holding member, a lever connected with a movable part of the magazine, connections between said lever and breech bolt holding member and between said lever and magazine holding member, means for manually operating the magazine holding member, and means for manually operating the breech bolt holding member.
13. A firearm including a frame having a chamber for a magazine, a magazine removably located in said chamber, means for holding the magazine in place, a breech-bolt located in the frame, a member located to hold the breech-bolt against movement, an operative connection between said member and the magazine holding means, and an actuating member connected with said holding member and magazine holding means and located in the path of movement of the magazine.
14. A firearm including a frame containing a magazine chamber, a magazine located in said chamber and having a movable follower, means for holding said follower against movement upon the removal of the last cartridge from the magazine and for releasing said follower for movement after the last cartridge has been fired, means for locking the holding means in its releasing position after the last cartridge has been fired, and a magazine holder connected with said follower to be operated thereby in its final movement.

GRANT HAMMOND.
